UNITED STATES PATENT OFFICE

144,379

DESIGN FOR AN ANT TRAP

Elston Curtis Hocker, Oakland, Calif.

Application October 1, 1945, Serial No. 122,440

Term of patent 3½ years

(Cl. D31—3)

To all whom it may concern:

Be it known that I, Elston Curtis Hocker, a citizen of the United States, residing at Oakland, in the county of Alameda and State of California, have invented a new, original, and ornamental Design for an Ant Trap, of which the following is a specification, reference being had to the accompanying drawing, forming part thereof.

Figure 1 is a perspective view of an ant trap showing my new design.

Figure 2 is a bottom plan view thereof.

Figure 3 is a view in side elevation of my new design.

I claim:

The ornamental design for an ant trap, as shown.

ELSTON CURTIS HOCKER.
